UNITED STATES PATENT OFFICE.

CROWELL L. WEMPLE, OF DILLON, MONTANA.

PITMAN CONNECTION.

No. 918,717.

Specification of Letters Patent.

Patented April 20, 1909.

Application filed October 20, 1906. Serial No. 339,890.

To all whom it may concern:

Be it known that I, CROWELL L. WEMPLE, a citizen of the United States, residing at Dillon, in the county of Beaverhead and 5 State of Montana, have invented new and useful Improvements in Pitman Connections, of which the following is a specification.

The invention relates to an improvement in pitman connections, designed particularly 10 for use with mowers, reapers, harvesters and the like.

The main object of the invention is the production of a pitman connection constructed to provide for its ready adjustment to take 15 up the wear of the bearings, and adapted to be secured in coupled or engaged relation through movement of a single lever.

The preferred details of construction of the present invention will be described in the following specification, reference being had particularly to the accompanying drawings, in 20 which:

Figure 1 is a plan view of my improved pitman connection, the parts being shown in 25 coöperative relation: Fig. 2 is a similar view with the parts shown in open relation. Fig. 3 is a detail longitudinal section, partly in elevation showing the pitman connection engaged with a projection from the cutter bar 30 of a mower or the like.

Referring particularly to the drawings, wherein similar reference numerals indicate like parts throughout the several views, 1 represents the pitman rod provided at one 35 end with the members 2 and 3 forming the parts of the pitman connection. These members are generally similar in construction, each comprising an elongated strip 4 designed to be secured to one side of the pitman 40 rod, and extended beyond the adjacent end of the pitman and terminally provided with an approximately semi-cylindrical head 5. One of the members, as 2, is inclined on the relatively inner face to overlie an adjacent 45 inclined face of the pitman rod, the member 2 being thickened in that portion overlying the inclined surface of the thickened and inclined portions extending in advance of the end of the pitman rod, the member 2 in advance 50 of the thickened portion being formed with an inwardly offset abutment 20. The other member, as 3, is extended beyond the free end of the rod in a portion of approximately equal thickness with that portion secured to the rod, said member being thickened in advance of said portion of equal

thickness to provide an abutment 21 alining with the abutment 20 of the member 2. If desired the side edges of the member 3 from the head 5 to a point inwardly beyond the outer edge of the pitman rod 1 may be provided with side edges 22, as shown in Figs. 1 and 2.

The members 2 and 3 are secured to opposing sides of the pitman rod, as clearly shown in the drawings, the heads of the respective members being disposed in transverse alinement beyond the proximate end of the rod. The end of the rod to which the members 2 and 3 are connected is reduced in width, as at 6, to provide a space between the end of the pitman rod and the strips 4 of the respective members. The reduced portion of the rod extends for some distance from the end thereof, thereby providing for independent lateral movement of the relatively forward ends of the strips 4.

Immediately forward of the end of the pitman rod one of the members of the connection, as 2, is thickened at 7 and formed with a transversely arranged threaded opening 8, the other member 3 being formed with a similar opening 9 alining transverse the connection with the opening 8. A bolt 10 is passed through the openings 8 and 9, being threaded at 11 for engagement with the threads of the opening 8, the remainder of the bolt being plane to provide for longitudinal movement relative to the member 3. The bolt 10 projects beyond the member 3 and is pivotally connected to an operating lever 12. The lever at the point of connection with the bolt is formed with a cam head 13, eccentrically pivoted to the bolt, a convenient means of connection being provided by forming the head 13 with a longitudinally disposed slot within which the bolt is mounted. The relatively outer surface of the member 3 surrounding the opening 9 is squared at 14 to provide for coöperation of the cam head of the lever.

It is to be understood that the cam head of the lever is of such size that when the lever is operated to move the operative point of the cam head into engagement with the squared surface of the member 3, said members 2 and 3 will be forced together, causing the heads 5 to approach each other.

In operative position the handle end of the lever 12 will rest against the relatively outer surface of the member 3, as shown in Fig. 1, and to guard against independent lateral

movement of the lever when in this position, I provide the end of the lever 12 with a notch 15, designed to embrace a pin 16 projecting from the surface of the member 3.

5 In the present instance the heads 5 are shown as interiorly concaved, as at 17, whereby to snugly embrace a ball 18 forming a terminal of an operating rod 19 leading to the cutter bar or other portion of the machine to be operated by the pitman. It is to be understood of course, that the head 5 may be of appropriate shape to engage the end of the machine part to be operated, the present form of heads being shown for convenience.

10 15 The lever 12, in addition to serving as a means for securing the members in coupled relation, provides also a means whereby the members may be relatively adjusted. The latter function is gained by connecting the lever directly to the bolt 10, so that the bolt may be readily turned to adjust it in the threaded opening 8 in the member 2, thereby increasing or decreasing the relative degree of movement of the respective members under the influence of the operating lever. To avoid lateral movement of the lever, with consequent tendency to turn the bolt 10, the lock, including the notch 15 and pin 16, is provided. By this construction when the 20 25 30 35 lever is in operative position, it is locked against lateral movement, and therefore, the lever forms a means for clamping the connecting members 2 and 3 in engaging position while at the same time locking the adjusting bolt against accidental movement.

Having thus described the invention, what I claim is:

30 35 The combination with a pitman rod having the opposing surfaces of its free end inclined toward each other, of a pitman connection including members secured to said opposing sides of the rods, each of said members projecting beyond the free end of the rod, one of

the members being extended beyond the free end of the rod in a portion of approximately 45 equal thickness with that portion secured to the rod, said member being thickened in advance of said portion to provide an abutment and being formed in advance of said abutment with a hemispherical projection, the 50 opposing member being thickened in that portion overlying the adjacent inclined face of the rod, said thickened portion extending in advance of the end of the rod and being inclined on its relatively inner surface to correspond to the inclination of the rod end, said member being formed in advance of the thickened portion with an inwardly offset abutment to aline with the abutment of the first mentioned member, and in advance of 55 said abutment with a hemispherical portion to aline with the hemispherical portion of the first mentioned member, that portion of the first member immediately in advance of the rod being formed with an opening of smooth 60 bore, the thickened portion of the second member being formed with a threaded opening alined with the opening of the first member, a bolt slidably mounted in the smooth bore opening and threaded for connection 65 with the threaded opening, a lever having a bifurcated end to straddle one end of the bolt, the relatively inner edges of the portions of the lever on opposite sides of the bolt being of cam formation to engage the 70 outer surface of one member and force said member toward the opposing member, and means carried by one of said members to engage the free end of the lever and secure the 75 same in operative position.

80 In testimony whereof, I affix my signature in presence of two witnesses.

CROWELL L. WEMPLE.
